DRAFTING INSTRUMENT

Robert M. Lindsay, Oak Park, Ill., assignor to
 Metal Specialties Manufacturing Co., Chicago,
 Ill., a corporation of Illinois

Application April 30, 1936, Serial No. 77,283

3 Claims. (Cl. 33—79)

This invention relates particularly to a parallel-movement drafting instrument adapted to be used on a drafting-board in lieu of a T-square.

The primary object is to provide a simple instrument of the character indicated, which is of universal adaptability, in the sense that the pneumatic holder with which the instrument is equipped is adapted to hold securely any simple ruling-device, such as a triangle, a French curve, a ruler, or any other similar device which presents an edge which will enable curves, whether straight or of other shape, to be drawn.

The invention is illustrated in a preferred embodiment in the accompanying drawings, in which—

Fig. 1 is a plan view of a drafting board with the improved drafting instrument applied thereto, the full lines indicating one position of the drafting instrument and the dotted lines indicating another position; Fig. 2, an enlarged broken sectional view taken as indicated in line 2 of Fig. 1, showing the manner in which the pneumatic-holder is secured to the parallel-movement head employed; Fig. 3, an enlarged broken sectional view taken as indicated at line 3 of Fig. 1; Fig. 4, a broken plan view showing the clamping nut removed from the threaded stud with which the pneumatic-holder is equipped, thus exposing the graduations for angular adjustment of the pneumatic-holder with respect to the parallel-movement head; and Fig. 5, a broken sectional view taken as indicated at line 5 of Fig. 4.

In the illustration given, A designates a drafting-board having a sheet A' of drafting paper mounted thereon; B, an adapter secured to one corner portion of the board, said adapter preferably comprising an attaching clip B' and a link-connecting clip B² detachably held by the clip B'; C, a parallel-movement head; D, a pneumatic-holder adjustably secured pivotally to the head C, for angular adjustment; E, a ruling-device, shown as a triangle, gripped by the pneumatic-holder; and F, jointed parallel-link mechanism connecting the clip B² and the head C.

The drafting-board C may be of any suitable construction.

The member B' of the adapter is shown as comprising a sheet metal member I which is secured to an edge of the drafting-board, as by screws I^a. The member I has a pair of resilient arms I^b formed integrally with the member I and projecting over the upper surface of the board A.

The member B² of the adapter is shown as a sheet metal clip which is provided with an inter-

mediate elevated link-bearing portion 2, supported by upright portions 2^a, and depressed end-portions 2^b adapted to be clamped between the spring-arms I^b and the upper surface of the drafting-board. The extremities 2^b of the adapter-member B² preferably are provided with perforations 3 which receive depressed lugs 4 with which the arms I^b are provided. The extremities of the arms are curved upwardly as indicated at 4^c. These extremities serve as finger pieces, by means of which the arms may be lifted to enable the member B² to be withdrawn.

The head C is shown as a yoke-like sheet metal plate having a pivot-portion 5 and a segmental portion 5^a to which the link-mechanism is attached. The pivot-portion 5 is preferably depressed below the plane of the segmental portion 5^a, as will be understood from Fig. 2. The pivot-portion 5 preferably is provided on its upper surface with radial graduations associated with degree-markings designated, generally, by the numeral 6. Any suitable degree-graduations may be employed. Preferably, a zero graduation appears at each end of a transverse line across the pivot-portion of the head, and the quarters making up the extremity of the pivot-portion are graduated in reverse directions from zero to 90°.

The pneumatic-holder D preferably comprises a sheet-metal bar, or cross-head, 7, from the end-portions of which depend suction-cups 7^a. The upper side of the member 7 is provided along the longitudinal center of the member with marks 8 disposed at opposite sides of the pivot-portion 5 of the head C. The member 7 is provided at its central portion with an upwardly projecting fixedly secured threaded stud 9 which extends through a pivot-perforation in the member 5 and is equipped above the member 5 with a clamping-nut 10.

The suction-cups 7^a are adapted to be pressed downwardly upon a plane surface with which the ruling-member is provided and caused to suctionally grip the ruling-member. The ruling-member may be of any suitable form. It may, for example, be a celluloid triangle. It has been found in practice that the holder D may be reliably secured to the member E, or any other desirable form of ruling-member, by the suction-cups employed.

As shown in Fig. 5, the suction-cup is composed of rubber having imbedded in its crown-portion the base of a short threaded stud 11 which extends through a perforation in the end-portion of the member 7 and is securely fastened by means 55

of a nut 11^a. A plurality of the suction-cups preferably is employed. As illustrated, the member 7 is equipped at each end with a suction-cup.

The height of the segmental portion 5^a of the head C preferably corresponds approximately with the height of the raised central portion 2 of the link-attaching clip B².

The parallel link-mechanism F comprises, in addition to the adapter-clip B² and the segmental portion 5^a of the head C, two pairs of parallel links 12 and 13 which are jointedly connected together by means of a joint-plate 14, shown as a ring punched from sheet metal. The initial pair of links 12 are connected with the clip 15 B² by pivot-rivets 15 and 16. The other ends of the links 12 are connected with the joint-disk 14 by pivot-rivets 17 and 18.

The links 13 are connected with the head C by pivot-rivets 19 and 20. At their other ends, the links 13 are connected with the joint-ring 14 by pivotal connections 21 and 22. The links 12 are shown as extending below the plane of the ring 14, and the links 13 are shown as extending above the plane of the ring 14.

The bearings for the links 12 and 13 afforded by the elevated clip 2 and the segmental portion 5^a of the head C are sufficiently extended to support the link mechanism well above the plane of the drafting board. As appears from Fig. 2, the cross-head D is adapted to swing in a plane beneath the head C to any desired position of angular adjustment.

In adapting the implement to the drafting board, a straight edge of the ruling device E may be placed parallel with an edge of the drafting-board. The pneumatic-holder D may be set at the zero mark and firmly clamped to the head C, and the pneumatic holder may then be pressed down firmly upon the member E. This establishes the straight edge in parallel relation with the edge of the drafting-board. The drafting-instrument may then be manipulated to bring the ruling-device E to any desired position, and the parallel movement will be maintained.

It is possible now to loosen the clamping nut 10 and turn the pneumatic-holder D to any desired position of angular adjustment. Then, by clamping the parts together, the desired angle of the straight edge is assured. The triangle E may now be moved to any desired position over the paper, and will always maintain the angle to which it has been set. Cross-hatching or ruling at any desired angle may be readily accomplished.

Obviously, the improved drafting implement is adapted to suctionally grip any ruling device which is provided with a suitable surface to make air-tight contact with the peripheral edges of the suction-cups. French curves, rulers of any desired shape, etc., may therefore be used in lieu of the triangle E, the improved drafting implement being thus universal in its application.

Heretofore, drafting machines employing parallel link mechanisms have been extensively used. However, such instruments have ordinarily been very expensive, the price being prohibitive for classroom purposes, or for popular purposes, generally. In such devices, rulers, or other ruling-devices, ordinarily are connected with the holder by dovetail connections, which are not only ex-

pensive but also do not lend themselves to universality.

The improved device may be manufactured so cheaply that it can be sold at a popular price, say at a retail price of \$1.00 to \$1.50. The improved drafting instrument is rather universal in its application to various forms of ruling devices, and may be reliably used. Its cost is only a fraction of the cost of drafting machines now on the market for similar use.

If desired, the adapter-member B' may be omitted. In such case, the adapter-member B² may be secured directly to the upper surface of the drafting-board by means of screws passing through the perforations 3. Thus, the member B² would become a single-member adapter.

The foregoing detailed description has been given for clearness of understanding only, and no unnecessary limitations should be understood therefrom, but the appended claims should be construed as broadly as permissible in view of the prior art.

What I claim as new and desire to secure by Letters Patent is:

1. A drafting instrument comprising: an adapter having means for attachment to a drafting board; a parallel-movement head; two pairs of parallel links and an interposed joint-plate connecting said pairs, one of said pairs being connected to said adapter and the other pair being connected to said head, whereby said head will be constrained for parallel-movement; said adapter comprising a clip provided with means for attachment to the drafting board, and a co-acting detachable bearing plate having pivotal connections with the initial ends of the initial pair of links; and a holder pivotally secured to said head and equipped with means for attaching a ruling-implement thereto.

2. A drafting instrument comprising: an adapter having means for attachment to a drafting board; a parallel-movement head; two pairs of parallel links and an interposed joint-plate connecting said pairs, one of said pairs being connected to said adapter and the other pair being connected to said head, whereby said head will be constrained for parallel movement; said adapter comprising a clip having means for attachment to a drafting board and having spaced resilient arms projecting over the board, and a link-connecting clip detachably held by said arms and having an elevated link bearing portion pivotally connected with the initial ends of the initial pair of links; and a pneumatic holder adjustably secured to said head and equipped with suction means for releasably attaching a ruling-implement thereto.

3. In combination: an adapter provided with means for attachment to a drawing board; a parallel-movement head linked to said adapter, said head having an elevated portion connected with the parallel-movement links and having a depressed pivotal portion to which said holder is secured for angular adjustment; and a pivotally-secured, angularly adjustable holder beneath and carried by said head, said holder being provided with means for securing an underlying ruling-implement thereto.

ROBERT M. LINDSAY.
